[57] CLAIM

The ornamental design for a food compartment for a lunchbox, substantially as shown and described.

DESCRIPTION

FIG. 1 is an exploded top perspective view of a food compartment for a lunchbox showing my new design. The portion in broken lines is a lunchbox in which the food compartment of my design would be accommodated.

FIG. 2 is a bottom perspective view of the cover thereof;

FIG. 3 is a top plan view thereof with the cover omitted;

FIG. 4 is a top plan view thereof; and,

FIG. 5 is a front or rear elevational view thereof on a reduced scale.

The bottom of the design is plane and unornamented.
